BELT BUCKLE

John Frank Jackson, Cleveland, Ohio

Application July 8, 1948, Serial No. 147,429

Term of patent 14 years

(Cl. D17—1)

To all whom it may concern:

Be it known that I, John Frank Jackson, a citizen of the United States, in the city of Cleveland, county of Cuyahoga, and State of Ohio, have invented a new, original, and ornamental Design for a Belt Buckle, of which the following is a specification, reference being had to the accompanying drawing, forming a part hereof.

Figure 1 is a plan view of a belt buckle, showing my new design; and

Figure 2 is an end elevational view of the same.

The face of the buckle is lined for color.

I claim:

The ornamental design for a belt buckle, as shown and described.

JOHN FRANK JACKSON.
